UNITED STATES PATENT OFFICE.

WALTER L. ENGELHARDT, OF ST. JOHNSVILLE, NEW YORK, ASSIGNOR TO F. ENGELHARDT & SONS, OF ST. JOHNSVILLE, NEW YORK, A FIRM.

DESIGN FOR A PIANO-CASE.

43,357.

Specification for Design.

Patented Dec. 24, 1912.

Application filed October 17, 1912. Serial No. 726,376. Term of patent 7 years.

To all whom it may concern:

Be it known that I, WALTER L. ENGELHARDT, a citizen of the United States, residing at St. Johnsville, county of Montgomery, and State of New York, have invented a new, original, and ornamental Design for Piano-Cases, of which the following is a specification, reference being had to the accompanying drawing, forming part thereof.

The figure is a perspective view of a piano case showing my new design.

I claim:

The ornamental design for a piano case as shown.

WALTER L. ENGELHARDT.

Witnesses:

ALPHONSE HEINRICH,
ROBT. S. CRAIG.
